DESIGN FOR A BUTTON OR SIMILAR ARTICLE

Morris L. Aaronson, New York, N. Y.

Application December 1, 1939, Serial No. 88,596

Term of patent 3½ years

To all whom it may concern:

Be it known that I, Morris L. Aaronson, a citizen of the United States of America, residing in New York city, in the Borough of Manhattan, county and State of New York, have invented a new, original, and ornamental Design for a Button or Similar Article, of which the following is a specification, reference being had to the accompanying drawing, forming part thereof, wherein:

I claim:

The ornamental design for a button or similar article, substantially as shown.

MORRIS L. AARONSON.
